(57) **CLAIM**

The ornamental design for a cartridge for a pipette device, as shown and described.

DESCRIPTION

FIG. 1 is an isometric view of a top, front, and left side of a first embodiment of a cartridge for a pipette system; FIG. 2 is a front elevational view of the cartridge for a pipette device of FIG. 1;

FIG. 3 is a rear elevational view of the cartridge for a pipette device of FIG. 1;

FIG. 4 is a left side elevational view of the cartridge for a pipette device of FIG. 1;

FIG. 5 is a right side elevational view of the cartridge for a pipette device of FIG. 1;

FIG. 6 is a top plan view of the cartridge for a pipette device of FIG. 1;

FIG. 7 is a bottom plan view of the cartridge for a pipette device of FIG. 1;

FIG. 8 is an isometric view of a top, front, and left side of a second embodiment of a cartridge for a pipette system; FIG. 9 is a front elevational view of the cartridge for a pipette device of FIG. 8;

FIG. 10 is a rear elevational view of the cartridge for a pipette device of FIG. 8;

FIG. 11 is a left side elevational view of the cartridge for a pipette device of FIG. 8;

FIG. 12 is a right side elevational view of the cartridge for a pipette device of FIG. 8;

FIG. 13 is a top plan view of the cartridge for a pipette device of FIG. 8; and,

(Continued)

FIG. 14 is a bottom plan view of the cartridge for a pipette device of FIG. 8.

The dash-dash-dash broken lines are included for the purpose of illustrating portions of the cartridge for a pipette device that form no part of the claimed design.

1 Claim, 8 Drawing Sheets
